UNITED STATES PATENT OFFICE

2,528,998

WATER AND FUEL HEATER

Ralph G. Bolin, Houston, Tex.

Application January 29, 1946, Serial No. 643,995

2 Claims. (Cl. 257—205)

1

My invention relates to heaters and more especially to heaters for water, fuel oil, natural gas and the like.

The object of my invention is to provide a heater to be heated by means of a steam coil therein and connected to a source of liquid such as water, fuel oil, natural gas and the like to be conducted into the heater and brought into contact with the heating coil.

Another object of my invention is to provide a boiler heated by a steam coil located therein and adapted to heat water, fuel oil, natural gas and the like conducted into the boiler and brought into contact with the heating pipe to save fuel and to prevent difficulties arising from the effect of freezing temperatures on fuel oil, natural gas and the like.

Other objects of my invention may appear in the following specification describing my invention with reference to the accompanying drawing illustrating a preferred embodiment of my invention. It is however to be understood that my invention is not to be limited and restricted to the exact construction and combination of parts described in the specification and shown in the drawing, but that such changes and modifications can be made which fall within the scope of the claims appended hereto.

In the drawing:

Figure 1 is a vertical sectional view through a heater according to my invention, parts being shown in elevation.

Figure 2 is a vertical sectional view of a modified form of the top of a heater according to my invention, and

Figure 3 is a plan view of a support for a heating coil used in the heater according to my invention.

Referring now to the drawing in detail the heater or boiler forming the subject matter of my invention has a hollow cylindrical body 10. A top 11 has a circumferential, downwardly extending flange 12, which surrounds the top end of the body 10. The top 11 is provided with a nipple 13 or similar fixture extending through the top and connected at its outer end with a pipe line 14 comprising a valve 15 and leading to a source of steam (not shown). Diametrically opposite the nipple 13 a second nipple 16 is provided on the top 11 and extends therethrough. With the outer end of nipple 16 a pipe line 17 is connected, adapted to return steam to the source thereof (not shown). A steam coil 18 is firmly connected at its intake end with the inner end of the first named nipple 13 and at its out-

let end with the secondly named nipple 16. A threaded hole is provided in the top 11 adapted to receive the threaded stem of a pressure gauge 19. An outlet pipe 20 is firmly connected with the top 11 and communicates therethrough with the interior of the body 10, when the top 11 is placed in position on the top end of the body 10. This is done after the heating coil 18 is connected to the nipples 13 and 16 and then the top is permanently fastened to the body by welding the flange 12 to the body 10 as indicated at 21 thereby producing a leak-proof connection between top 11 and body 10. A safety valve 22 is connected with the outlet pipe 20 which leads to any place (not shown) where the heated contents of the boiler, such as water, fuel oil, natural gas and the like, may be used.

A bottom section 23, having the shape of an inverted dome, rests on supporting legs 24. It is securely connected to the bottom end of the body 10 by welding, as indicated at 25, whereby a leak-proof connection between the body 10 and the bottom 23 is obtained. At its upper end the bottom has an inwardly extending circumferential flange 26. A suspended spider 27 has an outer ring 28 adapted to rest on the flange 26. From this ring 28 a plurality of arms 29 extend radially and inwardly and carry on their inner ends a somewhat elevated ring 30. The heating coil 18 rests on the arms 29 and the elevated ring 30 extends upwardly into said coil to center it within body 10 as shown in Figure 1.

Adjacent the lowest point of the bottom 23 an outlet 31 extends in a substantially horizontal direction therefrom, having a spigot 32 on its outer end.

Adjacent the upper edge of the bottom an inlet pipe 33 connects with the interior of the bottom. This inlet pipe leads from a source of liquid, such as water, fuel oil, natural gas or the like, to be heated and has a check valve 34 inserted therein to prevent back pressure of the liquid conducted by the pipe 33.

Figure 2 illustrates a modified form of the top and the top end of the body. In this modification the body 10—a has an outwardly extending circumferential flange 35 and the circumferential portion 36 of the top 11—a is formed so as to be adapted to rest on said flange 35. A ring gasket 37 is arranged between the flange 35 and the circumferential top portion 36. A plurality of bolts 38 having nuts 39 thereon seat the top firmly on top of the gasket 37, forming a leak-proof connection between top 11—a and body 10—a.

The heater, as described, operates as follows:

The valve 15 is opened and steam flows through the pipe 14 into the heating coil 18 and returns to its source through the outlet pipe 17. Liquid to be heated may be pumped through the inlet pipe 33 into the boiler where it will be heated by the steam in the heating coil 18 and will then leave the boiler through the outlet pipe 20.

Spigot 32 is used for draining and cleaning the boiler, and the check valve 34 prevents back pressure in the pump (not shown) feeding the liquid to be heated into the boiler.

Having described my invention, what I claim and desire to secure by Letters Patent is:

1. A heater for fluid comprising an upright hollow cylinder having a closed top and having closed inverted hemispherical bottom, a spider supported across the interior of said cylinder at the level of said inverted hemispherical bottom, annular flange rising centrally from said spider and providing a seat, a helical heating fluid coil having its lower end supportably confined within said seat whereby said coil is centered in said hollow cylinder, said heating coil rising to a point near said closed top of the cylinder, the upper end of said coil having an inlet terminal rising through said top for connection with a source of heating fluid, the lower end of said coil having a straight portion rising within said coil and having an outlet terminal on its upper end rising through said top, an inlet conduit for fluid to be heated traversing the side of said cylinder below said spider whereby fluid to be heated is charged into said cylinder to rise to the top thereof, and an outlet conduit for heated fluid traversing said cylinder top.

2. A heater for fluid comprising an upright hollow cylinder having a closed top and having closed inverted hemispherical bottom, a spider supported across the interior of said cylinder at the level of said inverted hemispherical bottom, annular flange rising centrally from said spider

and providing a seat, a helical heating fluid coil having its lower end supportably confined within said seat whereby said coil is centered in said hollow cylinder, said heating coil rising to a point near said closed top of the cylinder, the upper end of said coil having an inlet terminal rising through said top for connection with a source of heating fluid, the lower end of said coil having a straight portion rising within said coil and having an outlet terminal on its upper end rising through said top, an inlet conduit for fluid to be heated traversing the side of said cylinder below said spider whereby fluid to be heated is charged into said cylinder to rise to the top thereof, and an outlet conduit for heated fluid traversing said cylinder top, said inlet conduit having a check valve therein precluding escape of fluid therethrough from the interior of said cylinder, and a safety valve in said outlet conduit preventing escape of fluid from the interior of said cylinder below a predetermined pressure and permitting escape of heated fluid from the interior of said cylinder above the predetermined pressure.
